UNITED STATES PATENT OFFICE

2,313,350

SAFETY WASH TANK

William A. Lebus, Chicago, Ill., assignor to Protectoseal Company of America, Inc., Chicago, Ill., a corporation of Illinois

Application May 24, 1940, Serial No. 336,990

5 Claims. (Cl. 220—89)

This invention relates to wash tanks or receptacles, and particularly to the arrangement of closure means for such tanks or receptacles when used for volatile fluids in which articles may be dipped or submerged, and thereby subjected to the cleansing properties of the fluids.

One object of the present invention is to provide a tank for volatile fluids with improved, novel and efficient means automatically operable to quickly close the tank and stop combustion in the event of ignition of the fluid contents of the tank by accident or otherwise.

Another object of the invention is to provide novel means for releasably retaining the cover or closure of the tank in either open or closed position under normal conditions.

Another object of the invention is to provide a novel arrangement embodying heat responsive means operatively related to the retaining means and operable to render the latter ineffective to retain the tank closure in open position in the event of ignition of the fluid contents of the tank.

A further object of the invention is to provide a quick acting fusible connection between the cover and retaining means, and which when broken will permit the cover to close the tank.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is an elevational view partly in section of a wash tank and cover therefor, embodying features of the present invention;

Fig. 2 is a fragmentary sectional elevational view of a portion of the structure illustrated in Fig. 1 and taken substantially as indicated by the line 2—2 of Fig. 3;

Fig. 3 is an elevational view of the structure illustrated in Fig. 2 as viewed from the inside of the cover portion thereof; and

Fig. 4 is a transverse sectional plan view of a portion of the structure illustrated in Figs. 2 and 3 and taken substantially as indicated by the lines 4—4 thereof.

As illustrated in the accompanying drawing, the present invention is shown in its relation to a wash tank 5 adapted primarily to contain volatile fluid such, for example, as gasoline or the like, intended for washing or cleaning purposes, and is provided preferably with a perforated screen-like basket 6, in which articles to be washed may be placed and submerged in the fluid of the tank

to subject them to the cleansing properties of the fluid therein, the basket 6 being provided with handles 7 adapted to rest on suitable supports 8 mounted on the inner side of the tank 5 for permitting the basket and contents thereof to drain.

Mounted on one of the outer sides of the tank 5 is a stop 9, and pivotally mounted on the tank adjacent the stop, by means of a hinged bracket 11 and pintle pin 12, is a cover or closure member 10 indicated, as a whole, by the numeral 13 adapted to engage the stop 9, as illustrated in Figs. 1 and 2, when the cover is in open position.

It will be noted that when the cover 13 is in open position, as illustrated in Figs. 1 and 2, the greater portion of the cover is positioned on the side toward the body of the tank from a vertical line extending through the hinge pintle 12, in such a manner that when the cover is released from its open position, the weight of the cover will cause it to swing toward the tank and over the upper open portion thereof.

For controlling the position of the cover 13 with respect to the tank 5, and as clearly illustrated in Figs. 2 and 3, a guide bracket indicated, as a whole, by the numeral 14 is rigidly secured to the inner side of the cover 13 by means of rivets 15, and as clearly illustrated in Fig. 3, the bracket 14 is of shallow, substantially U-shaped cross section, having laterally extending, oppositely disposed flanges 16 formed thereon and spaced from the inner face of the cover 13. Mounted on the bracket 14 adjacent the upper portion thereof is an inwardly extending stud 17 having a transverse aperture formed therein adapted to receive suitable retaining means, such, for example, as a cotter pin 18 or the like.

Slidably mounted on the bracket 14 adjacent the inner side of the cover 13 is an elongated, substantially U-shaped member indicated, as a whole, by the numeral 19, having a laterally extending bight portion 21 adjacent its lower or inner end, and provided with spaced vertically extending substantially parallel leg portions 22 adapted to straddle the bracket 14 between the flanges 16 thereof and the adjacent inner face of the cover 13, the upper ends of the leg portions 22 being provided with a head indicated, as a whole, by the numeral 23 having parallel sleeve portions 24 provided with recesses 25 formed therein adapted to receive the upper ends of the leg portions 22 of the member 19, and rigidly secured to the head 23 between the lug portions 24 is a stud 26 having a laterally extending aperture formed therein adapted to re-

ceive suitable retaining means as for example, a cotter pin 27.

Pivotsly connected to the bight portion 21 of the member 19 is one end portion of a resilient member shown, in the present instance, as a substantially arcuate shaped flat spring 28 having its opposite end portion positioned in a recess or socket 29 formed adjacent the edge portion of the tank 5 by a strap 31 secured thereto by rivets 32 as clearly illustrated in Fig. 3.

For placing and maintaining the spring 28 under compression as illustrated by full lines in Fig. 2, the slidale member 19 is retracted, and a fusible link indicated, as a whole, by the numeral 33, is provided adjacent its end portions with apertures 34 adapted to receive the studs 17 and 26, respectively, and retained thereon against accidental displacement with respect thereto by means of cotter pins 18 and 27.

The link 33 is shown, in the present instance, as comprising oppositely disposed end elements or portions 35 overlapping each other intermediate the studs 17 and 26, as clearly illustrated in Fig. 2, and the elements 35 are secured together at their overlapping portions by means of a fusible metal indicated at 36, having a low melting point, adapted to fuse with the initial heat of combustion upon ignition of the fluid content in the tank.

It will be noted by reference to Fig. 2, that when the fusible link 33 is in position to connect the studs 17 and 26, the spring 28 is under compression, as illustrated by full lines in Fig. 2, and the bight portion 21 is at one side of the line A-B extending through the hinge pintle and the spring-and-tank connection adjacent the upper edge of the tank, thereby providing a structure whereby the cover 13 will be yieldingly retained in open position against the stop 9, and that when the bight portion 21 is positioned at the opposite side of the line A-B, the relationship of the spring connection with reference to the pintle 12, will serve to move the cover 13 toward its closed position as indicated by the dot-and-dash lines of Fig. 2.

It will be noted also that with the spring 28 under compression, as illustrated by full lines in Fig. 2, a constant strain is exerted on the link 33 tending to separate the studs 17 and 26, and also the end portions 35 of the link.

By such an arrangement, it will be apparent that upon fusing or melting of the metal 36, a quick separation of the portions 35 of the link will occur and permit the bight portion 21 of member 19 and the end portion of the spring 28 connected thereto, to assume the dotted line position shown in Fig. 2, thereby rendering the spring ineffective to retain the cover 13 in open position and permit the cover to move by gravity into tank closing position, thereby excluding oxygen from the tank and stopping combustion of the fluid contents thereof.

Thereafter, in order to place the device in condition for further use, it is only necessary to move the head 23 and member 19 inwardly toward the hinge side of the cover against the action of the spring 28, and by replacing the link 33 with a new link, the device may be continued in use until such time as the fusible metal of the link is again melted to render the spring 28 inoperative and permit the cover to close.

It will be observed from the foregoing description that the present invention provides a novel construction and arrangement whereby the cover or closure of the tank may, under normal condi-

tions, be retained in either open or closed position, and wherein novel means are provided for automatically closing the cover in the event of ignition of the fluid contents of the tank.

5 Furthermore, that the present invention provides a quick acting fusible connection between the cover and the retaining means, which when broken will permit the cover to close by gravity.

Obviously, the present invention is not limited to the precise construction and arrangement shown and described, as the same may be variously modified without departing from the spirit and scope of the invention as set forth in the appended claims.

15 What I claim as new and desire to secure by Letters Patent is:

1. In a device of the class described and in combination, a tank, a cover hingedly connected thereto, a stop for said cover when in open position, a bracket having a stud thereon secured to said cover, an elongated member slidably mounted on said bracket, said member having a laterally bent portion adjacent one end thereof and a head adjacent its opposite end portion, a stud on said head, a substantially arcuate shaped compressively stressed spring pivotally connected at one of its ends to the laterally bent portion of said member and at its opposite end pivotally connected to said tank, and a fusible link connecting said studs for releasably securing said elongated member in retracted position and to retain the stress in said spring, for all positions of the cover with said link intact.

35 2. In a device of the class described and in combination, a tank, a cover hingedly connected thereto, a stop for said cover when in open position, a guide bracket of shallow substantially U-shaped cross section secured to said cover, a stud on said bracket, an elongated U-shaped member having leg portions adapted to straddle said bracket, a head having a laterally extending stud thereon and secured to the free ends of said leg portions, a compressively stressed spring having its respective end portions connected to said tank and the bight portion of said elongated U-shaped member, and a fusible link connecting said studs and adapted to retain said spring under stress, for normally holding said cover yieldingly in open position.

45 3. In a device of the class described and in combination, a tank, a cover hingedly connected thereto, a stop for said cover when in open position, a guide bracket of shallow substantially U-shaped cross section secured to the inner side of said cover, said bracket having laterally extending oppositely disposed flange portions spaced from the cover, a stud on said bracket, an elongated U-shaped member having leg portions adapted to straddle said bracket between said flange portions and said cover, a head having a laterally extending stud thereon and secured to the free ends of said leg portions, a flat substantially arcuate compressively stressed spring having its respective end portions connected to said tank and the bight portion of said elongated U-shaped member, and a fusible link connecting said studs and adapted to retain said spring under compression for normally holding said cover yieldingly in open position.

60 4. In a device of the class described and in combination, a tank, a cover hingedly connected thereto, a stop on said tank adapted to be engaged by said cover when in open position, an elongated guide bracket of shallow substantially U-shaped cross section secured to the inner side

of said cover, said bracket having laterally extending elongated flange portions spaced from the cover, a laterally extending stud on said bracket, an elongated U-shaped member having leg portions adapted to straddle said bracket between the flange portions thereof and said cover, a head having a laterally extending stud thereon and secured to the free ends of said leg portions, a substantially arcuate compressively stressed spring having its respective end portions connected to said tank and to the bight portion of said elongated U-shaped member, and a link connecting said studs for retaining said spring under compression for yieldingly holding the cover in open position, said link comprising a pair of rigid end portions adapted to overlap each

other, and a fusible metal having a low melting point for securing said link portions together.

5. In a device of the class described, and in combination, a container member, a cover member therefor, a resilient element for yieldingly holding said cover member in open position, one end of which is pivotally carried by one of said members, the opposite end of said element being movable relative to the other member, and a fusible link operatively connecting the latter member and the adjacent end of said element to normally maintain said end in laterally fixed relation to such member while permitting pivotal movement relative thereto, and normally maintain said element under compression.
